CLAIM

The ornamental design for a plug socket, as shown and described.

DESCRIPTION

FIG. 1 is a perspective view of a plug socket showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof; and,

FIG. 8 is a rear, left, bottom side perspective view thereof. The broken lines in the drawings depict portions of the plug socket that form no part of the claimed design.
